UNITED STATES PATENT OFFICE

EMIL SCHANZE AND HEINZ KAFKA, OF BERLIN, GERMANY

TAPPING DEVICE FOR CLOSED VESSELS

Application filed June 24, 1929, Serial No. 373,415, and in Germany February 4, 1927.

This invention relates to an arrangement for tapping liquid by means of pressure from vessels. The arrangement utilizes an air pump in order to produce in the upper portion of the vessel a gas pressure, which forces the liquid through a siphon pipe to the discharge. The novelty of the invention consists in that in the siphon pipe a closing element is arranged which, in the lowest position of the piston of the air pump, is opened by the pressure exerted by this piston. By this arrangement according to the invention it is possible to produce by one operation the overpressure as well as to open the outflow, and to produce by repeated pumping first a comparatively high overpressure and then, by deeply depressing the piston, to make the liquid flow out with the aid of the accumulated pressure without fresh pumping.

An embodiment of the invention is illustrated by way of example in the only figure in the accompanying drawing.

On the vessel 1, i. e. a bottle, a split ring 2 and on the same a packing ring 3 are mounted. On the ring 2 a sleeve 4 is screwed into the upper end of which the tapping device 5 is screwed. This tapping device consists of a pump cylinder 6, in which a piston 7 can be moved in downward direction against the action of a spring 8. To the tapping device 5 a siphon pipe 9 is connected which has an enlarged portion 10 at the upper end. In this enlarged portion a liquid valve 11 with push rod 12 is accommodated, which is held in the closing position by the action of a spring 13. A channel 14 connects behind the valve 11 the enlarged portion 10 with the discharge 15.

The piston 7 has an air hole 16 through which air can flow in from the outer side at the ascending of the piston 7 through the hole 17, a suction valve 19 and a channel 21. The valve 19 is constructed like a disc movable in a chamber 18 and which, at the descending movement of the piston 7, closes the opening 17 and prevents thus from escaping the air

which has to be compressed in the cylinder 6. At the ascending movement of the piston the disc 19 bears against ribs 20 below it so that the air current flowing around the disc 19 can flow through the intervals between the ribs 20 to the channel 21 and into the cylinder 6. The piston is packed on the wall of the cylinder 6 by a leather disc 22, secured in position by a nut 23.

The compressed air flows through the channel 24 and through the ejecting valve 25, after overcoming the force of the counter spring 26, into the upper portion of the bottle 1. The valve 11 is pushed downward by means of the push rod 12 in opposition to the action of the spring 13 and opened as soon as the lowest portion of the piston 7 strikes against the top end of rod 12, which is then depressed by the descending piston.

In order to prevent the compressed air escaping from the bottle 1, a packing 27 is inserted between the socket 4 and the tapping device 5, and a packing 28 is inserted between the socket 4 and the neck of the bottle 1. The air compressed with the aid of the air pump 70 presses consequently upon the liquid level 29 and forces the liquid, instantaneously after the opening of the valve 11, to flow out through the siphon pipe 9 and the channel 14 to the discharge 15.

The invention may be applied not only to bottles but also for other receptacles. Different liquids, water, lemonade, benzine and others, can be tapped. The permanently tight closing and the overpressure in the bottle are important just for liquid liable to catch fire. For other liquids the fact is important that liquid can be tapped with the aid of the arrangement, however not filled into the bottle as long as the tapping device is on the same, this being material for the control of the nature of the contents of the vessel.

We claim:

A tapping device for closed vessels, comprising in combination with an air pump 90

adapted to produce an overpressure in the vessel, a tapping conduit consisting of a discharge on said tapping device of a siphon pipe in the vessel and of an enlarged top end 5 of said siphon pipe, a valve on said enlarged top end of the siphon pipe, a push rod upwardly projecting from said valve, and a piston in said air pump adapted to act upon the top end of said push rod of said valve when it is in its lowest compressing position.

10 In testimony whereof we affix our signatures.
